METAL STRIP CUTTER

Walter E. Northeutt, Chebanse, Ill., assignor to
Manco Mfg. Co., Bradley, Ill., a corporation of
Illinois

Application August 14, 1948, Serial No. 44,357

10 Claims. (Cl. 30—249)

1

This invention relates to cutting tools, and has to do with a tool for cutting metal strip such as metal strapping, commonly used for securing shipments of merchandise.

It is known to provide cutting tools of the character above referred to but, in general, the known tools are of rather expensive construction, do not possess adequate mechanical strength and are apt to tilt or twist in use, causing objectionable bending of the metal strip being cut or, in the case of rather thin strip, causing jamming of the strip between the jaws or cutting elements of the tool.

My invention is directed to a cutting tool of the character stated of comparatively inexpensive construction, which possesses adequate mechanical strength and assures ease and accuracy in cutting metal strip while avoiding possibility of jamming of the metal strip being cut between the cutting elements of the tool. More specifically, I provide a cutting tool comprising pivotally connected handle levers with associated cutting elements, the levers being provided with cooperating means whereby twisting or relative transverse movement of cutting elements during the cutting operation is effectively guarded against, thereby assuring ease and accuracy in the cutting operation and effectively guarding against distortion and jamming of thin metal strip between the cutting elements of the tool. Further, I provide a base for the cutting head of the tool having a flat undersurface of substantial area effective for preventing tilting of the tool during the cutting operation, the tool head comprising a rib extending upward from the base and providing, in cooperation with elements engaging about said rib, means effectively guarding against relative transverse movement of the handle levers, this rib being connected to the base by a reinforcing boss into which the slot for receiving the metal strip extends, the outer end portion of the slot being thereby substantially increased in width to reduce likelihood of distortion or bending of the metal strip in the latter portion of the cutting operation. Further objects and advantages of my invention will appear from the detail description.

In the drawings:

Figure 1 is a plan view of a cutting tool embodying my invention, the handle levers being broken away;

Figure 2 is a side view of the tool of Figure 1, with the handle levers broken away;

Figure 3 is a front view of the tool of Figure 1, with the handle levers broken away;

Figure 4 is a sectional view, on an enlarged scale, taken substantially on line 4—4 of Figure 1, the securing screw appearing in this view being shown in elevation;

Figure 5 is a front view of the forward portion of a modified form of cutting tool embodying my invention, the handle levers being broken away in major portion; and

2

Figure 6 is a front view of the tool of Figure 5.

The tool of my invention comprises two handle levers 11 and 14, referred to, for purposes of description, as the upper handle lever and the lower handle lever, respectively. The handle lever 11 is of I cross section for the major portion of its length and is provided, at its rearward end, with an upwardly offset handle 12, and, adjacent the forward end of handle 12, with outwardly tapering ears 13 offset downward a short distance from the body portion of the handle lever 11, the under faces of the ears 13 being flat for seating upon a flat surface such as a wall of a crate or container in which goods are shipped and which is secured by metal strapping, or any other flat surface. The ears 13, when seating on a flat surface such as that above referred to, reduce likelihood of lateral tilting of handle lever 11, as will be understood.

20 The forward end portion of the shank of handle lever 11 is thickened and offset to one side to provide a mounting element or pad 14 the other side of which is concaved as shown in Figure 4. This pad 14 receives a shank 15 extending from a head 16. The inner face of shank 15 is convexed so as to extend into the concaved side of pad 14, as shown in Figure 4, and the shank 15 is rigidly secured to pad 14 in a suitable manner, as by means of screws 15a, which may be socket headed screws of known type. The head 16 may be secured to handle lever 11 in any suitable manner so as to be rigid therewith and constitute a forward extension thereof, or may be formed integrally with lever 11, as will appear more fully later. The lever 11 may be of forged steel and the head 16 is formed of a good grade of tool steel, for which reason, particularly in the larger tools, the head 16 is formed separately from lever 11 and is suitably secured thereto.

40 The head 16 comprises a base element 17 and a rib 18 disposed lengthwise of, and extending upward from, base element 17 at one side thereof. This rib 18 is of substantially rectangular cross section and the head 16 is provided with an upwardly and rearwardly inclined slot 19 extending transversely thereof between rib 18 and base element 17. This base element 17 projects forwardly a material distance beyond rib 18, is slightly reduced in width at its forward portion 45 17a, and has its forward end beveled downward and forward at 18a for insertion between a metal band or strap and a crate or other shipping container about which metal strapping is secured. As will be understood, the head 16 is forced beneath the metal strip or strap until the latter is properly positioned within the slot 19 for cutting.

A reinforcing boss 20, integral with base element 17 and rib 18 connects the two and projects from one side of the rib, the rearward or outer portion of slot 19 extending into boss 20 and being there of materially increased width,

That provides increased supporting surface for the metal strip being cut, during the latter portion of the cutting operation, thereby reducing likelihood of bending or distortion of the metal strip as it is cut.

The handle lever 10 is provided, at its forward portion, with a hood 21 which may be formed integral with lever 10 and constitutes a forward extension thereof. This hood 21 is of substantially rectangular cross section and comprises side walls 22 and 23 connected, at their upper edges, by a bight element 24. The side surfaces of rib 18 are vertical and flat or planar, and the inner surface of side wall 22 of hood 21 is movable along the corresponding side surface of the rib 18 in contact therewith. A cutting blade 25, formed of high grade tool steel and shaped as shown in Figure 2, is disposed at the inner face of the other side wall 23 of hood 21 and is secured thereto, by a screw 26 passing through side wall 23 and threaded into blade 25 adjacent the rearward upper portion thereof, and a pivot bolt 27 passing through both walls 22 and 23 of hood 21 and through rib 18 and blade 25 adjacent the forward end thereof. The head of bolt 27 contacts the outer side of side wall 22 of hood 21 and a nut 28, threaded on the other end of bolt 27, contacts the outer side of wall 23 of hood 21, this nut 28 being preferably a self-locking nut of known type. The blade 25 is of such thickness that it seats against the adjacent side of rib 18 and is movable therealong in close contact therewith. The lower cutting edge of blade 25 is arched or curved toward slot 19, as will be clear from Figure 2, in which the lower edge of blade 25 is indicated by the reference number 30. The height of blade 25 is such that when handle lever 10, provided at its outer end with handle 31, reaches the end of its movement toward handle lever 11, blade 25 extends across and downward beyond slot 19 for the full length of the latter. Movement of handle lever 10 toward handle lever 11 is limited by a bumper 32, preferably formed of rubber or like elastic material, carried by a pin 33 slidable through an embossment 34 of handle lever 10, the outer end of this pin being peened over at 35. The bumper 32 is disposed to contact with a boss 36 of the pad or mounting element 14 of the lower handle lever 11.

As will be understood from what has been said, the tool handle levers 10 and 11 are pivoted together, adjacent the forward end of rib 18 and transversely thereof, by the bolt 27 for relative movement one toward and away from the other. In the use of the tool, the handle lever 10 is moved into such position that the blade 25 is clear of slot 19, and the tool is then positioned so that the metal strip or strap to be cut is disposed within the slot 19. The handle lever 10 is then moved toward the handle lever 11 and the metal strip is cut by the blade 25 in cooperation with the base element 17 of head 16. The curvature of the cutting edge 30 of blade 25 is such that the shear of the cut being made increases progressively toward the rearward or outer end of slot 19 in the cutting operation. That is advantageous in reducing the force required to cut the metal strip as the effective length of the handle lever 10 decreases, thereby facilitating cutting of the metal strip. By increasing the width of the slot 19 at the area of boss 20, increased support is provided for the metal strip at the area thereof last cut, thereby reducing likelihood of bending or distortion of that area of the strip as it is cut. As previously noted, the

underface of base element 17 of head 16 is flat or planar and is of much greater area than the horizontal cross sectional area of rib 18. That provides a firm foundation for the cutting head 16 during the cutting operation, thereby guarding against objectionable lateral tilting of the tool while the metal strip is being cut, which is conducive to ease and accuracy of the cutting operation. Further, the wall or flange 22 of hood 21 is in close contact with the corresponding side surface of rib 18, during the cutting operation, and blade 25 is in close contact with the corresponding side surface of rib 18 as it moves downward therealong for cutting the metal strip. The wall or flange 22 of hood 21 and the blade 25 thus cooperate with rib 18 effectively to restrain twisting or relative transverse movement of the handle levers 10 and 11 during cutting of the metal strip and assure that the cut will be effected without bending or jamming of the strip between the blade 25 and the cutting head, particularly when cutting thin metal strip or strapping, which is desirable for obvious reasons.

In the modified form of tool shown in Figures 25 5 and 6, the cutting head 16a is formed integrally with the lower handle lever 11a, and the cutting blade 25a is formed integrally with side wall or flange 23a of hood 21a, as a downward extension thereof. This flange 23a, including blade 25a, of hood 21a, is disposed in close contact with the corresponding side surface of rib 18, and the other flange 22a of hood 21a is disposed in close contact with the corresponding side surface of rib 18. The construction and operation 30 of the tool of Figures 5 and 6 are otherwise the same as in the tool of Figures 1 to 3, inclusive, and need not be described in greater detail. Since the cutting blade 25a and the cutting head 16a should be formed of a good grade of tool steel, 40 and are formed integrally with the handle levers 16a and 11a, respectively, which also are formed of the same grade of steel, that is, high grade tool steel, the construction shown in Figures 5 and 6 ordinarily would be employed for the smaller 45 sizes of tools only, due to the expense involved.

It will be understood that changes in detail may be resorted to without departing from the field and scope of my invention, and I intend to include all such variations, as fall within the scope 50 of the appended claims, in this application in which the preferred forms only of my invention have been disclosed.

I claim:

1. In a tool for cutting metal strip, a pair of 55 similarly directed handle levers pivoted together at their forward ends for relative movement about a transverse axis one toward and away from the other, one of said levers having a transverse slot extending rearward beyond said pivot axis and open at its forward end for reception of metal strip, and a cutting blade carried by the other lever disposed to transverse said slot and having a cutting edge disposed to cut metal strip in said slot progressively from the forward edge 60 to the strip toward the rearward edge thereof whereby the strip as it is cut is urged toward the rear of said slot.

2. In a tool for cutting metal strip, a pair of 70 similarly directed handle levers pivoted together at their forward ends for relative movement about a transverse axis one toward and away from the other, one of said levers having a transverse slot extending rearward beyond said pivot axis and open at its forward end for reception 75 of metal strip, a cutting blade carried by the

other lever at one side of said one lever and disposed to traverse said slot, said blade having a cutting edge disposed to cut metal strip in said slot progressively from the forward edge of the strip toward the rearward edge thereof, and cooperating interfitting elements carried by said levers restraining them against relative transverse movement in the cutting operation, said interfitting elements comprising an element fixed to said other lever and extending along said one lever at the side thereof opposite to said blade.

3. In a tool for cutting metal strip, a pair of handle levers, means pivoting said levers together at their forward ends for relative movement about a transverse pivot axis one toward and away from the other, said levers both extending in the same direction from said pivot axis, one of said levers having a transverse slot extending rearward beyond said pivot axis and open at its forward end for reception of metal strip, a cutting blade carried by the other lever disposed to traverse said slot and having a cutting edge disposed to cut metal strip in said slot progressively from the forward edge of the strip toward the rearward edge thereof, and cooperating interfitting elements carried by said levers restraining them against relative transverse movement in the cutting operation.

4. In a tool for cutting metal strip, a lower handle lever provided with a forwardly extending head comprising a base element and an upwardly extending rib with a transverse slot between them open at its forward end for reception of metal strip, an upper handle lever pivoted at its forward end to said rib for movement toward and away from said lower lever, a cutting blade carried by said upper lever movable along said rib at one side thereof in contact therewith and disposed to traverse said slot, and an element carried by said upper lever movable along said rib at the other side thereof in contact therewith, said element and blade in cooperation with said rib restraining said levers against relative transverse movement in the cutting operation.

5. In a tool for cutting metal strip, a lower handle lever provided with a forwardly extending head comprising a base element and an upwardly extending rib with a transverse slot between them open at its forward end for reception of metal strip, said rib being of substantially rectangular cross section with planar side surfaces, an upper handle lever having a forwardly extending member straddling said rib provided with an element movable along one side of said rib in contact therewith, said member being pivoted at its forward end to the forward end of said rib transversely thereof, and a cutting blade carried by said member movable along said rib at the other side thereof in contact therewith and disposed to traverse said slot.

6. In a tool for cutting metal strip, a lower handle lever provided with a forwardly extending head comprising a base element and an upwardly extending rib with a transverse slot between them open at its forward end for reception of metal strip, said rib being of substantially rectangular cross section with planar side surfaces, an upper handle lever having a forwardly extending hood substantially conforming to and movable over said rib in contact with one side thereof, said hood being pivoted at its forward end to the forward end of said rib transversely thereof, and a cutting blade carried by said hood movable along said rib at the other side thereof in contact therewith and disposed to traverse said slot.

7. In a tool for cutting metal strip, a lower handle lever provided with a forwardly extending head comprising a base element and an upwardly extending rib with a transverse slot between them open at its forward end for reception of metal strip, said rib being of substantially rectangular cross section with planar side surfaces, and an upper handle lever having a forwardly extending member straddling said rib pivoted thereto transversely thereof and comprising two side walls movable along the sides of said rib in contact therewith, one of said side walls providing a cutting blade disposed to traverse said slot.

8. In a tool for cutting metal strip, a lower handle lever provided with a forwardly extending head comprising a base element and an upwardly extending rib with a transverse slot between them open at its forward end for reception of metal strip, said base element projecting a material distance beyond said rib at one side thereof and being connected to said one side of said rib by a reinforcing boss into which said slot extends and is there of materially increased width, an upper handle lever pivoted at its forward end to said rib transversely thereof, and a cutting blade carried by said upper lever movable along said rib at the other side thereof and disposed to traverse said slot.

9. In a tool for cutting metal strip, a lower handle lever provided with a forwardly extending head comprising a base element and an upwardly extending rib with a transverse slot between them open at its forward end for reception of metal strip, said base element projecting a material distance beyond said rib forward and to one side thereof and being connected to said one side of said rib by a reinforcing boss into which said slot extends and is there of materially increased width, an upper handle lever pivoted at its forward end to said rib transversely thereof, the under face of said base element being planar providing a supporting surface of materially greater width than said rib and the forward end of said base element being beveled downward and forward, and a cutting blade carried by said upper lever movable along said rib at the other side thereof and disposed to traverse said slot.

10. In a tool for cutting metal strip, two handle levers pivoted together adjacent their forward ends, cooperating base and cutting members carried by said handle levers respectively at the forward ends thereof, said base member having a flat under face and being beveled downwardly and forwardly at its forward portion for insertion beneath metal strip to be cut, one of said handle levers having a flat surface at its outer side adjacent the cutting area of the tool, and a guide member of substantially rectangular cross section fixed to the other handle lever extending therefrom across said one handle lever and along said flat surface in close proximity thereto and in cooperation therewith restraining said handle levers against relative transverse movement outwardly.
